(57) **CLAIM**

I claim the ornamental design for a solar powered LED fly trap, as shown and described.

DESCRIPTION

FIG. 1 is a perspective view of a solar powered LED fly trap of the present invention;

FIG. 2 is a top view thereof;

FIG. 3 is a bottom view thereof;

FIG. 4 is a side elevation view thereof;

FIG. 5 is another side elevation view thereof;

FIG. 6 is a front view thereof;

FIG. 7 is a rear view thereof;

FIG. 8 is a rear view of the shroud of the present invention with the base removed;

FIG. 9 is a perspective view of the shroud thereof;

FIG. 10 is a perspective view of a second embodiment of a solar powered LED fly trap of the present invention;

FIG. 11 is a top view thereof;

FIG. 12 is a bottom view thereof;

FIG. 13 is a side elevation view thereof;

FIG. 14 is another side view thereof;

FIG. 15 is a front view thereof;

FIG. 16 is a rear view thereof;

FIG. 17 is a rear view of the shroud of the present invention with the base removed; and,

FIG. 18 is a perspective view of the shroud thereof.

The broken lines in the figures are for contextual purposes or show the environment and form no part of the claimed design.

1 Claim, 16 Drawing Sheets
